UNITED STATES PATENT OFFICE

JOSEPH S. MARZAK, OF BALTIMORE, MARYLAND, ASSIGNOR TO LION BROTHERS COMPANY, INC., OF BALTIMORE, MARYLAND, A CORPORATION OF MARYLAND

HAT

Application filed November 15, 1929. Serial No. 407,317.

The invention relates to the type of washable fabric, hat or cap worn by Navy and other sailors. It consists of a central crown usually of cotton duck and an upturned circular brim which is stiffened by circumferential sewing so that when properly laundered it retains its position with a reasonable degree of firmness and regularity. However, a very small amount of wear causes the edge 5 to become wavy or wobbly and to get out of shape so that very frequent laundering is necessary to make the article fairly presentable in its appearance.

The object of the present invention is to support the edge and cause the cap to retain 15 its shape and appearance without in any way interfering with or reducing its washability or decreasing its length of life when frequently laundered. Its durability is, in fact, 20 increased and it is given a distinctive appearance as the result of the improved construction.

To this end the brim which is formed of several thicknesses of duck, is stiffened by 25 means of a cord sewed to the edge and concealed therein in and after the manner to be described. A hat or cap embodying the features of the invention is illustrated in the accompanying drawings.

In the drawings:

Figure 1 is a side elevation of the finished cap.

Figure 2 is a top plan of the same.

Figure 3 is a section on a vertical radial plane indicated by the line 3—3 in Figure 2.

Figure 4 is a view corresponding to Figure 3 showing the brim separate from the remainder of the hat and flattened in a plane which may be termed vertical in its relation 40 to the position of the hat when worn.

Figure 5 is a similar section showing the cord sewed to the brim fabric, the brim being unfinished and the cord uncovered.

Referring to the drawings by numerals 45 each of which is used to indicate the same or similar parts in the different figures, the sailor's hat or cap illustrated in detail in Figure 3 consists of a crown portion 1, the band or sweatband 2 and a brim 3. This brim to 50 which the invention relates consists mainly

of three pieces of fabric, i. e., a closed ring or band of thin stiffening material which may be termed buckram, which may be heavily sized, the same being indicated by reference character 4, a second band of canvas which 55 may be sewed to the strip 4 by a line of stitching 5, the canvas band being indicated by reference character 6 and a double band 7 or ring of drilling or similar material which forms the external lower edge of the brim and 60 is like the remainder of the hat fabric, i. e., the crown.

This band is folded at the top, the free edges being at the bottom in Figure 5. The inside sheet of fabric of the band 7, referring 65 to it in its present position, Figure 5, is indicated by reference character 8, and the outside sheet by reference character 9.

The respective strips or rings of fabric 4, 6 and 7 the latter having its top edge formed 70 by the fold, are laid together with their top edges in registration. A cord 10 is laid along the outside surface of the double band 7 near the top and the cord 3. The straps or bands of fabric 4, 6, 7 are then sewed together by a line of stitching 11, passing through and through all four members, i. e., the cord, the fabric 4 and 6, and the two layers of fabric 7. The outer sheet or layer 9 of the folded strip 7 is then swung outwardly to the left and upwardly about the cord 10 and then over the top edges 12 and 14 of the bands 6 and 4, respectively, and down on the right side of this assembly as seen in Figure 4 being laid against the right 80 hand surface of the buckram strip 4 which it covers. The cord being thus covered, the strips of fabric 4, 6 and 7, the latter composed of the two layers 8 and 9 and the latter being now on the right or inside and the layer 8 on the left or outside so that layers 8 and 9 form the two surfaces of the brim,

are then sewed together by a series of lines of stitching 15 extending circumferentially around the hat and laying parallel to each 95 other and spaced apart in the direction of the height or width of the brim as shown in section in Figure 4 and elevation in Figure 1, in plan as to the inside of the brim in Figure 2 and in elevation as to the inside of the 100

brim in Figure 3, other lines of stitching 16 similarly laid connect the edges 17 and 18 of the sheets or layers 9 and 8 below or beyond the width of the stiffening strips 4 and 6. 5 These portions 17 and 18 are then turned up and the crown 1 and band 2 are joined to them after the manner illustrated in Figure 3 or in any suitable manner in accordance with the regular practice in the construction of such hats.

10 I have thus described specifically and in detail a hat or cap and the manner of combining and constructing the same in order that said structure may be fully understood, 15 however, the specific terms herein are used descriptively rather than in a limiting sense, the scope of the invention being defined in the claim.

What I claim as new and desire to secure 20 by Letters Patent is:

A sailor's or similar fabric hat having an upwardly projecting brim formed of layers 25 of stiffening material and hat material, a stiffening cord at the top edge connected to said stiffening material and said hat material; which latter is double and has a fold line at the top, by a line of stitching extending through said folded cover material near the fold and through said stiffening material 30 near the top and through the cord, said hat material covering the brim on both sides and also covering the cord, said fold being secured between the cord and the top edge of the stiffening material by said stitching, 35 the brim being further formed with a series of lines of stitching extending through and through said respective layers of material and around the brim circumferentially and spaced apart in the direction of the width 40 or height of the brim.

Signed by me at Baltimore, Maryland, this 8th day of November, 1929.

JOSEPH S. MARZAK.
